(57) **CLAIM**

The ornamental design for a combination of thermometer probe and probe box, as shown and described.

DESCRIPTION

FIG. 1 is a front perspective view of a combination of a thermometer probe and a probe box showing my design, showing the probe box accommodating the thermometer probe and the probe box in a closed position.

FIG. 2 is a front perspective view of the combination of the thermometer probe and the probe box in FIG. 1, showing the probe box accommodating the thermometer probe and the probe box in an open position.

FIG. 3 is a front perspective view of the combination of the thermometer probe and the probe box showing my design, showing the thermometer probe removed from the probe box and the probe box in an open position.

FIG. 4 is a front perspective view of the thermometer probe of the combination of the thermometer probe and the probe box showing my design.

FIG. 5 is a rear perspective view of the thermometer probe in FIG. 4.

FIG. 6 is a front elevation view of the thermometer probe in FIG. 4.

FIG. 7 is a rear elevation view of the thermometer probe in FIG. 4.

FIG. 8 is a left side elevation view of the thermometer probe in FIG. 4.

FIG. 9 is a right side elevation view of the thermometer probe in FIG. 4.

FIG. 10 is a top plan view of the thermometer probe in FIG. 4.

FIG. 11 is a bottom plan view of the thermometer probe in FIG. 4.

FIG. 12 is a front perspective view of the probe box of the combination of the thermometer probe and the probe box showing my design.

FIG. 13 is a rear perspective view of the probe box in FIG. 12.

(Continued)

FIG. 14 is a front elevation view of the probe box in FIG. 12. FIG. 15 is a rear elevation view of the probe box in FIG. 12. FIG. 16 is a left side elevation view of the probe box in FIG. 12.

FIG. 17 is a right side elevation view of the probe box in FIG. 12.

FIG. 18 is a top plan view of the probe box in FIG. 12; and, FIG. 19 is a bottom plan view of the probe box in FIG. 12. The broken lines in the figures show portions of the combination of thermometer probe and probe box that form no part of the claimed design.
